Primary Examiner — Philip S Hyder(74) *Attorney, Agent, or Firm* — Alan D. Kamrath;
Kamrath IP Lawfirm, P.A.(57) **CLAIM**

The ornamental design for head of a pry bar, as shown and described.

DESCRIPTION

FIG. 1 is a perspective view of a head of a pry bar showing my new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken lines depict portions of the head of a pry bar in which the design is embodied that are not considered part of the claimed design.
